(57) **CLAIM**

The ornamental design for a spectrophotometer, as shown and described.

DESCRIPTION

FIG. 1 is a perspective view of a first embodiment of the spectrophotometer of the present invention, in which a sample holder is mounted therein.

FIG. 2 is a top view of the spectrophotometer shown in FIG. 1.

FIG. 3 is a bottom view of the spectrophotometer shown in FIG. 1.

FIG. 4 is a side view of the spectrophotometer shown in FIG. 1 illustrating the side of FIG. 1 facing the viewer.

FIG. 5 is a side view of the spectrophotometer shown in FIG. 1 illustrating the side of FIG. 1 facing away from the viewer.

FIG. 6 is an end view of the spectrophotometer shown in FIG. 1 illustrating the end facing the left hand side of the page.

FIG. 7 is an end view of the spectrophotometer shown in FIG. 1 illustrating the end facing the right hand side of the page.

FIG. 8 is a perspective view of a second embodiment of the spectrophotometer of the present invention.

FIG. 9 is a top view of the spectrophotometer shown in FIG. 8.

FIG. 10 is a side view of the spectrophotometer shown in FIG. 8 illustrating the side of FIG. 8 facing the viewer.

FIG. 11 is a side view of the spectrophotometer shown in FIG. 8 illustrating the side of FIG. 8 facing away from the viewer.

FIG. 12 is an end view of the spectrophotometer shown in FIG. 8 illustrating the end facing the left hand side of the page; and,

FIG. 13 is an end view of the spectrophotometer shown in FIG. 8 illustrating the end facing the right hand side of the page.
